United States Patent Office

Des. 185,839

Patented Aug. 11, 1959

185,839

BUILDING

Howard W. Frank, Los Angeles County, Calif., assignor to Huntington Ice Cream Co., Burbank, Calif., a corporation of California

Application March 25, 1958, Serial No. 50,174

Term of patent 14 years

(Cl. D13—1)

FIG. 1

FIG. 2

Des. 185,839

PAGE 2

Fig. 3

Fig. 4

Figure 1 is an elevational view of a building showing my new design, as seen from one side thereof;

Fig. 2 is an elevational view of the other side thereof;

Fig. 3 is a front elevational view thereof;

Fig. 4 is a rear elevational view thereof; and

Fig. 5 is a left front perspective view thereof.

I claim:

The ornamental design for a building, substantially as shown.
